[57] CLAIM

The ornamental design for a flower pot cover, substantially as shown and described.

DESCRIPTION

FIG. 1 is a plan view of the flower pot cover showing our new design.

FIG. 2 is a front elevational view thereof.

FIG. 3 is a rear elevational view thereof.

FIG. 4 is a side elevational view thereof.

FIG. 5 is a side elevational view similar to FIG. 4, but showing the side opposite that shown in FIG. 4.

FIG. 6 is a bottom plan view thereof, the pattern which is partially shown is understood to repeat across the outer surface.

FIG. 7 is an enlarged plan view of the pattern shown in FIG. 6.

The flower pot cover has no substantial thickness.
